CLAIM

The ornamental design for a toy glider, as shown and described.

DESCRIPTION

FIG. 1 is a top plan view of the toy glider in its open position showing our new design;

FIG. 2 front elevational view of the toy glider of FIG. 1;

FIG. 3 is a left side elevational view of the toy glider of FIG. 2, the right side being identical;

FIG. 4 is a rear elevational view of the toy glider of FIG. 1;

FIG. 5 is a bottom plan view of the glider of FIG. 1; and

FIG. 6 is a perspective view of the glider of FIG. 1 in its closed position.

FIG. 2

FIG. 4

FIG. 5

FIG. 6
